UNITED STATES PATENT OFFICE.

EDWIN I. GOLDRING, OF NEW YORK, N. Y., ASSIGNOR TO STEHLI FABRICS CORPORATION, OF NEW YORK, N. Y., A CORPORATION OF NEW YORK.

WOVEN FABRIC AND THE PROCESS OF ITS MANUFACTURE.

Application filed December 7, 1927. Serial No. 238,314.

My present invention relates generally to a woven fabric and coordinately relates to the method for its production.

As my invention in one of its aspects involves the association in a single weave of differently formed yarns, one of which I will herein term a filamentary yarn and the other of which is known as twisted or crepe yarn, I will premise that a filamentary yarn is one formed directly from straight cocoon filaments; for example, filaments being simultaneously withdrawn from sixteen cocoons. These filaments are caused to adhere to each other by the natural sericin or gum of the cocoon, to form what I have termed a filamentary yarn which is straight or un-twisted, and this term whenever hereinafter employed, will be so understood unless the context calls for a different interpretation. During the boil off of the fabric containing filamentary yarns, the natural gum of the cocoon, which served as the binder, is removed to a great extent and the individual filaments of the yarn tend to spread so that the yarn after the weaving and the boil off spreads and becomes fluffy.

A twisted or crepe yarn is formed by twisting together two or more filamentary yarns, the crepe yarn employed by me using three filamentary yarns twisted sixty-four times to the inch. The twist puts a permanent twist or kink in the yarn. Before weaving the yarn is set by steam, and woven while set. After the completed fabric is boiled off, the crepe yarn again becomes twisted or crinkled, and gives to the fabric a crinkly or pitted effect. Crepe yarn is closely compacted and might be termed hard and brittle.

In the drawings forming part of this application, I have illustrated the employment of wefts or picks all of the same character, and of warps some of which are filamentary yarn and others of which are twisted or crepe yarn, and I will so describe my invention. It will be understood, however, that this is done merely for purposes of illustration and is not to be construed in any sense as limitative, unless called for by the language of the claims or by the state of the prior knowledge or prior art.

One of the objects of my invention is the

production of a woven fabric in which a striped effect is produced wholly by the employment of both filamentary yarn and twisted or crepe yarn for the warp and is independent of all other factors.

My present invention is to be distinguished from the treatment of yarns with a mordant and the use of such mordant-treated yarns with other yarns not so treated, so that in the dyed fabrics the treated yarns will give a different effect from the others, and by proper association of these yarns a striped effect is produced. It is also to be distinguished from the employment of differently colored yarns for the production of the stripes. So also is it to be distinguished from taffeta having a satin stripe in the production of which two weaves are employed, and in which the striped effect is produced by a difference in weave.

In accordance with the practice of the embodiment of my invention herein illustrated and described, I employ two warp beams, one carrying the filamentary yarns and the other the twisted or crepe yarns. The threads of yarns on each beam are in spaced groups with the groups on one beam positioned so as to be intermediate the groups on the other warp beam. The twisted or crepe yarns are warped on the beam in regular order, two right twist yarns following two left twist yarns, and so on, the twists being distinguished by a slight tint to one which ultimately disappears. The process herein is illustrated, for example, only as intended to produce stripes of equal width throughout the fabric and each group of yarns on both beams therefor extends along its beam for the same length. There are, however, much fewer yarns in each group on the twisted or crepe warp beam. The wefts or picks are all illustrated as being twisted or crepe yarn. The weave is a simple taffeta weave throughout, only one shed being used, which is common to both warp beams and which sheds both the filamentary yarns and the twisted yarns. The warp beams are let off differentially, because one of the warp beams carries twisted rough yarn or threads and the other carries a smooth, soft yarn or thread.

When the woven fabric is boiled off, the

twisted yarns or warps resume their twist, and give a crinkly effect. The filamentary yarns, however, due to the boil off, lose a great deal if not most of the natural binder 5 associated therewith from the cocoon, and each spreads considerably and becomes larger and fluffier. In other words, the former becomes crinkly or wavy; the latter sort of inflates or fluffs up and becomes 10 softer, due to the fact that the numerous filaments of which it is made, spread.

When the fabric woven as above described is dyed a single color, I find that although the weave is the same throughout and the 15 yarn alike in all respects throughout, except that some warps are twisted and others straight, that there is thereby produced a fabric with beautiful stripes, distinguished from each other optically by one group of 20 stripes giving the effect of a darker shade and the intermediate group of stripes giving the effect of a lighter shade, even though as a fact they are dyed alike and at the same time.

This striping effect results from a number 25 of factors. One of these is the fact that those bands having the filamentary warps are relatively opaque due partly to the greater number of warp yarns per unit length of weft as compared with the number per unit in the 30 adjacent bands having twisted warps, and partly to the fact that the filamentary yarns spread after the boil off, whereas the twisted yarns do not act that way. They crinkle. Another fact is a difference in the light reflecting and absorbing characteristics of fabric portions having a twisted warp as compared with those having a filamentary warp. The crinkly fabric is dull looking.

One of the important features of my invention is the production of a fabric having 40 a striped effect, by the employment of warps all of which are made of the natural cocoon filament and differ from each other only in the manner in which the warp yarns are 45 formed, some warps being twisted and others straight, all the warps however having the same or a common shed.

Another important feature of my invention is the production of a fabric giving the 50 appearance of being made up of lighter and darker stripes, which appearance is not dependent on a change in the weave or any change in the dye, or any treatment which will cause a common dye to act differently 55 on different yarns or on different portions of the fabric.

Another object of my invention is the production of a fabric which while woven the same throughout, and dyed the same throughout, and made of the same filament throughout, nevertheless gives the effect of lighter 60 stripes interspersed with darker stripes.

The remarkable striped effect of the fabric produced as above set out I attribute to a 65 great extent to the difference in the light

transmitting and light reflecting characteristics between those portions having filamentary warps and those portions having twisted or crepe warps.

Another feature of my invention therefore 70 is in the production of a fabric giving the appearance of lighter and darker stripes, which is wholly or partly the result of the difference in the light transmitting and light reflecting characteristics of different portions 75 of the fabric.

It will be understood from what has already been said that one group of spaced stripes has a crepe weft and a twisted or crepe warp and the stripes intermediate have 80 a twisted or crepe weft and a filamentary warp. The bands having the crepe warps form a sheer fabric which is relatively brittle and less resistant to strain and stresses than are those bands or fabric portions having 85 the filamentary warps which form a much stronger, relatively opaque and more flexible fabric.

My claim to invention in this application is directed to the production of a composite 90 fabric having portions which have the characteristics of one, associated with portions which have the characteristics of the other, so that each gains by the presence of the other. The opaque fabric benefits by the sheerness of 95 the other, and the sheer fabric benefits from the reinforcing action of the other. In addition, while each of these fabrics by itself may be attractive, the pattern effect resulting from their association in the manner set 100 forth is something absolutely new and different from that given by either.

As the apparatus developed by me for the production of the fabric herein disclosed as my invention is not claimed herein, but is to 105 be the subject-matter of a separate application, it has been shown only diagrammatically and merely for purposes of illustrating how the fabric is produced.

For the attainment of those objects and features as have already been pointed out or as may hereinafter appear, I have illustrated my new fabric along with a diagrammatic showing of an apparatus employing my new process for its production, and reference is 115 made to the drawings wherein:—

Fig. 1 shows diagrammatically the manner of and the apparatus for warping the un-twisted raw silk.

Fig. 1^A shows the warp beam carrying the 120 untwisted yarn.

Fig. 2 is a similar showing of the manner of and apparatus for warping the crepe or twisted yarn.

Fig. 2^A shows the warp beam carrying the 125 twisted or crepe yarn.

Fig. 3 is a section across the fabric parallel to a weft showing the binding or weave.

Fig. 4 shows diagrammatically in top plan view a loom employed in my process; and 130

Fig. 5 is a face view of a section of my fabric on an enlarged scale, showing adjacent stripes.

Referring first to Fig. 3 of the drawing, which shows the binding or weave, reference character 10 is applied to the weft or pick which is made of crepe yarn, and the picks are of the same character throughout the fabric. The warps are of two characters, the reference character 11 being applied to the twisted warps and 12 to the straight or filamentary warps. These warps are arranged in groups, alternately, first one group of straight or filamentary warps and then a group of twisted or crepe warps, and so on. In Fig. 3 of the drawing I have only shown for purposes of simplicity of illustration, the employment in each group of crepe warps of only five of such warps, and in each group of straight or filamentary warps the use of sixteen of such warps. The illustration of this specific number of each group is merely, as stated, for purposes of simplicity of illustration, because as a matter of fact a stripe which will be produced by this number of warps will be an extremely narrow one and as a matter of fact in order to produce a stripe of the character shown in Figs. 4 and 5 of the drawing, the number of warps in each group are many times the number shown. However, Fig. 3 of the drawing does show that where it is desired to attain a striped effect, with the stripes all of equal width, the relative proportion between the two groups as shown in Fig. 3 should be maintained. The linear space occupied by each group is, however, the same where the strips are of the same width. It will be observed, on viewing Figs. 3 and 5 of the drawing, that the weave illustrated is a simple taffeta one-two, one-two weave throughout the fabric, this weave being common to both groups of warps.

In the apparatus shown in Fig. 4 of the drawing, there are employed two warp beams, the warp beam A having warped thereon the untwisted raw silk and the warp beam B having warped thereon the twisted or crepe silk. These are warped on the beams in spaced groups, each group corresponding to a stripe to be produced and being of the width of the stripe which it is intended or desired to produce; and these groups are staggered one with relation to the other. The reference character A' is applied to the groups of untwisted raw silk and the reference character B' to the groups of twisted or crepe yarn. The shedding mechanism is shown at C, all the warps of both beams being shed together so as to produce a fabric having a common weave throughout. At D is shown diagrammatically the shuttle box apparatus by which the picks are thrown, these picks all being of the same character throughout, namely, of

the twisted or crepe yarn. At E is shown the take up beam.

In connection with this apparatus I have found that in view of the fact that some of the warps are rough, stiff and compact, and other warps are smooth and soft, there must be a differential action in the left off of the two beams. I have not illustrated this part of my apparatus because it is not essential to this invention herein claimed, and make reference thereto only for the purposes of a full understanding of the broader steps of my process.

Figs. 1 and 2 show diagrammatically the warping machine for the two characters of yarn employed. The warping of the untwisted yarn is shown at Fig. 1, and for the purposes of illustration I have shown forty spools F on the frame G so as to provide forty untwisted warps 12 in each group A'. In Fig. 2 I show the manner of warping the crepe beam, twenty-seven spools H being shown for illustration so as to provide twenty-seven crepe yarns 11 in each group to form the group B'. It will be understood, of course, that the use of twenty-seven spools on one and forty spools on the other is not intended to give the relative proportion of the numbers in each group, because that would depend both upon the actual as well as the relative widths of the different stripes which it is desired to obtain, the proportion shown in Fig. 3 of the drawing being found satisfactory by me in the production of a fabric having stripes of equal width.

In Figs. 1^A and 2^A I show the warp beams A and B fully warped and a comparison of these beams will show the staggered relationship of the groups.

At the lower end of Fig. 4 of the drawing I show the completed fabric giving a striped effect, in which the stripes 12', having crepe warps only, alternate with the stripes 11' which show the fabric sections having the twisted warp, Fig. 3 showing this diagrammatically.

In Fig. 5 of the drawing I have attempted to show on an enlarged scale what the fabric looks like, the fabric section or stripe 11' having twisted wefts or picks and straight or filamentary warps 11, and the adjacent section 12' having the same twisted wefts or picks as the section 11' but having all its warps made of the twisted yarn 12.

I have already referred hitherto to the general character of the straight or filamentary warps and the crepe or twisted warps or yarns and their manner of formation, and it is unnecessary to repeat this.

The fabric of the character shown in Fig. 5 of the drawing, and woven in accordance with the process illustrated in Fig. 3, when boiled off causes the filamentary warp threads 11 to spread and become fluffy, because of the fact that in such boil off the

1 natural gums present are removed to a great extent. This causes the warps 12 woven in the sections 12' of the fabric to swell and become fluffy. On the other hand, after 5 the boil off of the fabric, the twisted warps 11 of the sections 11', which prior to the weaving process were set by steam, again resume their crinkled condition and each warp becomes more drapy than it was immediately before the boil off. The tendency of 10 the filaments of the warps 11 to separate and to swell, as already referred to, is compared with what might be termed a reverse action on the part of the twisted warps 11, particularly when accompanied by the use of a 15 greater number of straight or filamentary warps or straight wefts per linear unit than twisted warps 11, will make the fabric sections or stripes 11' relatively opaque and the adjacent fabric sections or stripes 12' relatively transparent. As a matter of fact, in 20 the embodiment disclosed herein the proportion between the two warps used per linear unit and the actual numbers of each that are used per linear inch is such as to make the 25 crepe or filamentary sections or stripes 12' opaque and the adjacent twisted warp threads 11' transparent.

This association of sections or stripes of 30 the character set forth gives to the composite fabric the remarkable effect because of the contrast between the stripes and this contrast is materially enhanced because of the background which can be seen through 35 the transparent sections 11'.

The fabric sections or stripes 12' form a fairly smooth, soft, strong, flexible fabric, whereas the fabric sections or stripes 11' form a rougher, sheer fabric.

40 It will be understood that the use of the natural filament of the cocoon is described as employed herein although phases of my invention do not require this. It will furthermore be understood the production of a 45 longitudinal stripe necessitates that the variation in the yarn be in the warp threads and it is for this reason that it has been so illustrated.

Having thus described my invention and 50 illustrated its use, what I claim as new and desire to secure by Letters Patent is:—

1. A woven fabric comprising alternate zones, one of the zones comprising a group of warp threads, each warp thread being 55 made up of straight silk filaments held together by the natural gum of the cocoon, and an adjacent zone comprising a group of twisted crepe silk warp threads, said groups of warp threads being held together 60 by wefts whereby in the finished fabric and after the boil off, the warp threads of the first mentioned zone become disengaged and the warp threads of the second mentioned zone become kinked so as to produce a contrasting striped effect between the zones.

2. A woven fabric comprising alternate zones, one of the zones comprising a group of warp threads, each warp thread being made up of straight silk filaments held together by the natural gum of the cocoon, and an adjacent zone comprising a group of twisted crepe silk warp threads, said groups of warp threads being held together by wefts, the fabric being similarly interlaced throughout, whereby in the finished 70 fabric and after the boil off, the warp threads of the first mentioned zone become disengaged, and the warp threads of the second mentioned zone become kinked so as to produce a contrasting striped effect between 75 the zones.

3. A woven fabric comprising alternate zones, one of the zones comprising a group of warp threads, each warp thread being made up of straight silk filament held together by the natural gum of the cocoon, and an adjacent zone comprising a group of twisted crepe silk warp threads, the individual warp threads of said first mentioned group being positioned closer to 80 together than the threads of the other group, said groups of warp threads being held together by wefts whereby in the finished fabric and after the boil off, the warp threads of the first mentioned zone become 85 disengaged, and the warp threads of the second mentioned zone become kinked so as to produce a contrasting striped effect between 90 the zones.

4. A woven fabric comprising a weft, and 95 warps arranged in alternate groups to form stripes, the individual weft threads and the warp threads of one of said groups being twisted crepe silk yarn, and the individual warp threads of said other group being silk 100 filaments held together by the natural gum of the cocoon, and being, relative to the threads of the first group, spaced closer to each other, the interlacing of the fabric being uniform throughout the length of the 105 wefts, whereby in the finished fabric and after the boil off, the portions of said fabric defined by the warps of twisted crepe silk will be relatively more transparent than the 110 portions defined by the warps of silk fil- 115 ments.

5. The process of forming a striped woven fabric which includes the steps of weaving a fabric by the employment as warps of groups, of twisted crepe yarns alternating 120 with groups of yarns, the last mentioned yarns being each made up of silk filaments held together by the natural gum of the cocoon, and then boiling off the fabric so formed whereby the twisted yarns will kink 125 and the filaments of the other warp yarns will spread.

6. The process of forming a woven fabric with contrasting stripes which includes the 130 steps of weaving a fabric by the employment

as warps of groups of twisted crepe yarns alternating with groups of yarns, the last mentioned yarns being each made up of silk filaments held together by the natural gum of the cocoon, and boiling off the fabric so formed whereby the twisted yarns will kink and the filaments of the other warp

yarns will spread, and then applying a dye to said fabric, whereby a fabric will be produced having stripes of different shades. 10 In witness whereof I have signed this application.

EDWIN I. GOLDING.

as warps of groups of twisted crepe yarns alternating with groups of yarns, the last mentioned yarns being each made up of silk filaments held together by the natural gum of the cocoon, and boiling off the fabric so formed whereby the twisted yarns will kink and the filaments of the other warp

yarns will spread, and then applying a dye to said fabric, whereby a fabric will be produced having stripes of different shades. 10

In witness whereof I have signed this application.

EDWIN I. GOLDING.
